UNITED STATES PATENT OFFICE.

BENJAMIN OSHMAN AND DAVID OSHMAN, OF NEW YORK, N. Y.

COMBINED BRUSH WITH COMBS.

Application filed September 12, 1927. Serial No. 218,937.

This invention relates to a combined brush with combs, of the type wherein these two elements are utilized simultaneously and in cooperation for improved and efficient combining and brushing of the hair, and its principal object is to provide a simplified, efficient, and improved article for this purpose.

Another object is to provide such article with improved means for mounting the combs thereon and demounting them therefrom, to permit separate use of the combs when desired, and to permit separate, efficient, and convenient cleansing of the combs.

Another object is to provide such article with simplified, efficient, and improved means for demounting the combs when in operative state and placing them in the brush in inoperative condition without projecting.

A further object is to provide such article with positive locking means for said combs when in operative or inoperative positions.

A further object is to provide such article with an improved mirror device, which will permit separate use of the mirror, and which will guard the mirror and at the same time provide an additional mirror for use without requiring removal of said first mirror.

Other objects and advantages will herein-after appear.

In the accompanying drawings,—

Figs. 1 and 2 are plan views of the article showing its parts in different positions.

Fig. 3 is an end elevation of the article, shown partially in cross section.

Fig. 4 shows a cross-sectional side elevation of the article.

Fig. 5 is a perspective view showing the locking devices of the article.

Figs. 6 to 11 show modifications of parts of the article.

The article 1 comprises the usual body 2, a handle 3, and a brush 4 set in said body. The body proper comprises two sections 5, 6 which are joined to each other by a connecting hinge 7 at their ends, whereby these sections open and close relative to each other, as shown in Fig. 1, wherein the section 6 is shown broken away for clearness of illustration. In the sides of the body-section 5 are hingedly mounted a pair of combs 8, which may be swung to either a projecting operative condition, shown in the lower side of Fig. 1, or to an inoperative state within the section, as shown at the upper side of this figure. Each comb 8 is hinged by means of a pin 9 thereof entering a ledge 10 of section 5 and another pin 11 thereof dropping into a slot 12 in a lower ledge 13. The slot 12 is closed to prevent dislocation of the hinge-pin 11, by means of a leaf spring 14 hinged at 15 being swung to the position shown in Fig. 1. When it is desired to remove the comb for separate use or cleansing, the spring 14 is swung back to the dot-and-dash position shown. To set the article for combined use of the brush 4 with the combs 8, the latter are both swung to the outward projecting position, shown at the lower side of section 5 in Fig. 1, and then the section 6, which carries the brush 4, is swung about the hinge 7 to a position in locked engagement with the section 5, as shown in Figs. 2, 4, this closing and locking up of said sections serving to efficiently lock the combs 8 in their operative condition, as shown in lower side of Fig. 1. The locking and unlocking of the body-sections 5, 6, is accomplished by means of a device 16 located in a cavity 17, extending partially between the two sections and partially within the handle 3. Said device, Figs. 4, 5, comprises a bolt 18 longitudinally slidable in a guide-way 19 under tension of a spring 20, and an actuating pin 21 projecting from the bolts passing through a guide-slot 22 in the handle. The end of section 6 carries a hasp 23, which, upon closing of the two sections 5, 6, strikes the bevelled head 24 of bolt 18 and thereby automatically locks the two sections, disposing the locking parts in the position shown in Fig. 4. To release the sections for unlocking, it merely requires withdrawing of the actuating pin 21 in slot 22 contrary to the upward pressure of the spring 20. When it is desired to maintain the combs out of use, as when it is desired to use the brush only, or for the protection of the combs when the article is not in use, it merely requires opening of the body-sections 5, 6, swinging the combs inwardly to the position shown at the upper side of the section 5 in Fig. 1, and then locking said sections together again, in which manner the combs are held locked in inoperative state within the body 2. It will be noted that the locking-end 24a of the body-section 6 is dovetailed, and the handle portion 25 which it engages is complementarily configurated, whereby the body-sections 5, 6, are thus held firmly thereat against lateral dislocation, in cooperation with the hinge 7.

In the body 2 and above the combs 8, Figs. 3, 6, is formed a pocket 26 in which slides a mirror 27, whereby the latter may be either inserted when not in use, or withdrawn for use unconnected with the brush-body. The back 28 of this brush-body is made of a non-crackable material, such as celluloid, which is mirrorized, whereby this back not only acts as a guard for the mirror 27, when the latter is slid into the brush-body, but at the same time affords mirroring utility without requiring withdrawing of the actual mirror 27 from the body. In the cavity 17 is located a locking device for the mirror 27. Said device, Figs. 4, 5, comprises a spring-bar 30, secured in place by a screw 31, which bar carries a pin 32 that is thus continually pressed upwardly by said spring-bar, and an operating pin 33 projects upwardly from the bar 30 through the body-section 5 and its terminal is lodged within a finger indentation 34 in the back of the body 2. When the mirror 27 is slid into its pocket 26 in the body, the pin 32 automatically enters a hole 35 thereof and thereby effectively and positively locks the mirror in this position. Upon pressing downwardly of the terminal of pin 33 in the indentation 34 the pin 32 releases the mirror 27 for withdrawal of the latter for separate use.

If desired the body-section 5 may be provided with a pair of pins 36, over which may be slipped a double-toothed comb 37, Fig. 7 the teeth of which would thus project outwardly in the manner shown in Figs. 2, 6, and this comb may be therefore utilized in place of the two combs 8. The double-toothed comb may be also mounted in operative state upon the brush-body by means of providing it with a ridge 38, Fig. 8, arranged to slip into a channel 39, Fig. 9, with which the body-section 5 may be also provided.

In the modification shown in Figs. 10, 11, the hinge-slot 12 is lined with a slotted metal cylinder 40, and the comb 8 is provided with a thin portion 41 to permit it to slip through the slot 42 of cylinder 40 whereby the comb may be mounted in hinged state upon section 5 by slipping the portion 41 in slot 42, then pushing the comb so as to insert the pin 9 in its hole and ledge 10, and the pin 11 then incidentally falling in the cylinder 40 to substantially hinge the comb 8 thereat.

Variations may be resorted to within the scope of the invention, and portions of the improvements may be used without others.

Having thus described our invention, we claim:

1. A hair brush having a body for the brush, said body comprising sections hinged to each other, means to lock and unlock said sections, a pair of combs hinged to one of said sections adapted to be swung to either

projecting operative positions or to inoperative positions within said body, and said sections when locked maintaining said combs locked in either of said positions. 65

2. A hair brush having a body for the brush, said body comprising sections hinged to each other, means to lock and unlock said sections, a comb hinged to one of said sections adapted to be swung to either projecting operative position, or to inoperative position within said body, and said sections 75 when locked maintaining said comb locked in either of said positions.

3. A hair brush having a body for the brush, said body comprising sections hinged to each other, means to lock and unlock said sections, a pair of combs hinged to one of said sections adapted to be swung to either projecting operative positions or to inoperative positions within said body, said sections 80 when locked maintaining said combs locked 85 in either of said positions, and means to remove said combs from their hinged state for use disconnected from said body.

4. A hair brush having a body for the brush, said body comprising sections hinged to each other, means to lock and unlock said sections, a comb hinged to one of said sections adapted to be swung to either projecting operative position, or to inoperative position within said body, said sections when locked maintaining said comb locked in either of said positions, and means to remove said comb from its hinged state for 95 independent use.

5. A hair brush having a body for the brush, said body comprising sections hinged to each other, means to lock and unlock said sections, a pair of combs hinged to one of said sections adapted to be swung to either projecting operative positions or to inoperative positions within said body, said sections when locked maintaining said combs locked in either of said positions, and said locking means being located within said body and having an operative position at the exterior 100 of the body. 105

6. A hair brush having a body for the brush, said body comprising sections hinged to each other, means to lock and unlock said sections, a comb hinged to one of said sections adapted to be swung to either projecting operative position, or to inoperative position within said body, said sections when locked maintaining said comb locked in either of said positions, and said locking 115 means being located within said body and having an operative portion at the exterior of the body.

Signed at the city of New York, in the county of New York, and State of New York 125 this 31st day of August, A. D. 1927.

BENJAMIN OSHMAN.
DAVID OSHMAN.
